UNITED STATES PATENT OFFICE.

ADOLF CARL KLUGE, OF NEW YORK, N. Y.

DESIGN FOR A SET OF SILK-WOVEN INITIALS.

No. 38,642.

Specification for Design.

Patented June 25, 1907.

Application filed May 22, 1907. Serial No. 375,178. Term of patent 14 years.

To all whom it may concern:

Be it known that I, ADOLF CARL KLUGE, a citizen of the United States, residing at New York, in the county of New York and State of New York, have invented a new, original, and ornamental Design for a Set of Silk-Woven Initials, of which the following is a specification, reference being had to the accompanying drawing, forming part thereof.

The drawing is a view of a set of silk woven initials, showing my design.

I claim—

The ornamental design for a set of "silk woven initials," as shown.

ADOLF CARL KLUGE.
